CLAIM

We claim the bilevel sump sink, as shown and described.

DESCRIPTION

FIG. 1 is a perspective view of a bilevel sump sink in accordance with the invention.

FIG. 2 is a top elevation view of the bilevel sump sink shown in FIG. 1; and,

FIG. 3 is a cross-sectional view of the bilevel sump sink shown in FIGS. 1 and 2 and is taken about the line 3—3 shown in FIG. 2.

Broken lines shown in the drawings are environment and do not form part of the claimed design.
